Application May 19, 1948, Serial No. 27,876

15 Claims. (Cl. 3—2)

1

The present invention relates to a new and improved knee lock for artificial limbs.

An important feature of the invention consists in associating with the knee joint of an artificial limb, a releasable locking mechanism including means for maintaining the thigh member and the calf member of an artificial limb in a vertical or straight position when the wearer is taking a forward step, and providing means operable by the application of pressure on the ball or toe of the foot to release the locking mechanism. In order to re-engage the locking connection of the thigh member with the calf member, when the thigh member and calf member are in vertical or aligned position, it is necessary for the wearer to apply weight on the heel of the foot which causes the locking mechanism to be moved to its latched position, and thus prevent bending of the thigh member and the calf member at the knee joint or buckling of the knee as the wearer proceeds to take a forward step. As the body of the wearer approaches a vertical position above the artificial leg, his weight shifts over the knee center and it is no longer necessary for the artificial leg to require the knee lock to prevent it from buckling at the knee joint. Therefore, as the body of the wearer moves forward, depression of the toe or ball of the foot causes the knee lock to unlatch allowing the wearer to bend the knee so as to begin the next forward step, thus providing simple, efficient and positive means for flexing the knee joint, and for preventing the collapse of the limb when the weight of the wearer is placed on the knee joint in the act of walking.

A further object consists in associating with the knee lock mechanism, a lost motion connection which is operable when the locking pawl is moved out of engagement with a latch on the thigh member and the foot member is returned to its normal position, to prevent engagement of the pawl with the latch upon the return movement of the foot member. Additionally, yieldable means are provided when the pawl is moved into locking engagement with the latch for allowing return of the foot member to its normal horizontal position without disturbing the locking connection of the pawl with the latch member so that the thigh member and the calf member will be maintained in vertical alignment until the toe of the foot is again depressed.

Another object consists in providing a knee lock mechanism which is connected to the calf member and includes a pawl arranged to be moved into and out of engagement with pawl

2

receiving means on the thigh member. A control bracket is fixed to the lock mechanism and has means rotatably connected thereto which are operatively connected to the pawl, and also to an operating rod which is connected to the foot member, so that upon rocking of the foot member relative to the calf member from its normal position and in one direction when the thigh member and calf member are in alignment, for actuating the rotatable means to move the pawl into locking engagement with the latch means, and upon rocking the foot member from its normal position and in an opposite direction, for actuating the rotatable means to move the pawl out of engagement with the latch means.

Other objects and advantages of the invention will become apparent from the following description when taken in conjunction with the accompanying claims and drawings.

20 Referring to the drawings in which are disclosed several preferred embodiments of the invention:

Figure 1 is a vertical sectional view of an artificial limb constructed in accordance with the present invention, showing the thigh portion locked to the calf portion and the parts in the position they assume when the wearer takes a forward step.

Figure 2 is an enlarged detailed rear view of the knee joint shown in Figure 1.

Figure 3 is a sectional view taken substantially along the line 3—3 of Figure 1.

Figure 4 is an enlarged vertical sectional view taken substantially along the line 4—4 of Figure 2.

Figure 5 is an enlarged detailed sectional view taken substantially along the line 5—5 of Figure 4.

Figure 6 is an enlarged detailed sectional view taken substantially along the line 6—6 of Figure 4.

Figure 7 is a sectional view taken substantially along the line 7—7 of Figure 6.

Figure 8 is a detailed side view showing the position of the friction lever, transfer pin, and operating rod when the parts are in locking position.

Figure 9 is a view similar to Figure 8 showing the parts when the locking mechanism is moved to its released position.

Figure 10 is an enlarged sectional plan view taken substantially along the line 10—10 of Figure 1.

Figure 11 is a sectional view taken substantially along the line 11—11 of Figure 10.

Figure 12 is a perspective view of the transfer lever.

Figure 13 is a perspective view of the friction lever.

Figure 14 is a perspective view of the control bracket.

Figure 15 shows the position of the artificial limb as the leg is moved forward, and shows the locking pawl in full lines just prior to the operating rod taking up the lost motion and moving the locking pawl into engagement with the bottom of the thigh member.

Figure 16 shows the position of the artificial limb and the locking mechanism when the body of the wearer is moved over the artificial limb with the parts in locked engagement, and also shows in dotted lines the release of the locking mechanism after the application of pressure on the ball of the foot and when the knee is bent to begin the next forward step.

Figure 17 is a vertical rear section of a modified form of artificial leg constructed in accordance with the present invention.

Figure 17a is an enlarged vertical sectional view taken substantially along the line 17a-17a of Figure 19.

Figure 18 is a rear view of the knee joint structure shown in Figure 17.

Figure 19 is a sectional view taken substantially at right angles to that shown in Figure 17, and

Figure 20 is an enlarged sectional view taken substantially along the line 20-20 of Figure 19.

Referring to the drawings, the artificial limb constructed in accordance with the present invention includes a hollow thigh member or section 21, a hollow calf member 22, and a foot member 23, which may be made of any suitable light, durable composition or metal. The bottom of the thigh member is curved as at 24 and shaped to fit within the upper hollow portion of the calf member 22 in order to provide a movable knee joint and permit free movement of the knee joint without danger of a garment of the wearer becoming caught between the joint. Extending upwardly from opposite sides of the calf portion 22 adjacent the top thereof, are a pair of fixed bearing lugs 25 (Fig. 2) having transverse aligned openings through which extends a fixed knee bolt 27 provided with enlarged head portions 28 at its opposite ends that bear against the lugs 25. The thigh member 21 adjacent the knee joint 24 is rotatably mounted on the knee bolt 27 and the bottom of the knee joint 24 is provided with a notch or recess 29. A metal guard plate 18 having an opening 19 registering with the recess 29, may be secured by the screws 20 to the bottom of the knee joint 24, (Fig. 3).

The locking mechanism associated with the artificial limb may include a metal member or bar 30 having at its upper end a lateral projecting portion 31 (Fig. 4) provided with a transverse opening 32 through which loosely extends the knee bolt 27. The bar is preferably formed with a depending channel-shaped portion or member 33 which extends downwardly through a central slot 34 in the rear of the thigh member 21, and has spaced parallel sides 35 (Fig. 3). The depending portion 33 is firmly secured to the rear wall of the calf section in any suitable manner such as by the retaining screws 36. A flat spacer spring 37 may be connected at its lower end as at 38 (Fig. 4) to the portion 33 and has its upper portion extending over and engaging the underside of a transverse pin 39 as at 40. A locking pawl or lever 41 is pivoted at one end as at 42 to the

spaced sides 35 of the channel portion 33 of the member 30, and is provided at its opposite end with a nose 43 which is arranged to be moved into the recess or detent 29 when the thigh member 21 and the calf member 22 are in alignment, so as to lock these members together and prevent buckling of the artificial limb at the knee joint. The end of the pawl 41 may be faced with a leather covering or the like 41' to prevent scraping of the pawl on the knee in the event the lock does not entirely disengage. The forward wall of the slot 34 may be provided with a rubber buffer 44 that bears against the bar 30 when the latter is in its vertical position. A control bracket or member 45 is provided at one end with a bent flange portion 46 (Fig. 14) which extends into the channel member 33 (Fig. 3) and may be secured thereto by the retaining bolt 36 and the spaced screws 47. The opposite end of the control bracket 45 terminates in an enlarged circular head 48 having a central opening 49. A friction lever 50 is provided at one end with an enlarged circular portion 51 having an opening 52 (Fig. 13) which registers with the opening 49 in the control bracket 45. The lever 50 has intermediate its ends, an enlarged opening 53 and terminates at one end thereof in a laterally extending flange 54 formed with a vertical through opening 55 through which loosely extends a slideable connecting rod 56 having a head 57 at its lower end and positioned below the flange 54. The upper end of the rod 56 extends into an opening 58 in a boss or member 59 so as to be rigidly secured thereto such as by welding or the like. The upper end of the boss 59 is bifurcated so as to form the spaced arms 60 which overlap the pawl 41 and are pivotally connected thereto by the pin 61 (Fig. 5). Surrounding the rod 56 and confined between the flange 54 and the boss 59 is a coil expansion spring 62 which provides a lost motion connection between the friction lever 50 and the pawl 41 in a manner and for the purpose that will subsequently be described. A transfer lever or member 63 is positioned adjacent the control bracket 45 opposite to the friction lever, and has at one end an opening 64 which registers with the opening 49 in the control bracket, and has extending laterally and outwardly therefrom a transfer pin or stud 65 which extends into the opening 53 in the friction lever and is of much smaller diameter than the opening 53 so as to be loosely mounted therein for the purpose of permitting lost motion or movement of the transfer lever a limited or predetermined distance before operating the friction lever. The pin 65 may carry a flexible rubber sleeve 65' also of smaller diameter than the opening 53 and arranged to engage the wall thereof upon vertical movement of the rod 78. The transfer lever 63 is also formed with an opening 66 through which rotatably extends a screw 67 that is threaded as at 68 to a sleeve 69 to permit independent movement of the transfer lever relative to the sleeve 69. A spring metal washer 70 is positioned adjacent the friction lever 50 and has a central opening which registers with the opening 52 on the control lever and may be spaced therefrom by a friction fiber washer 71. A shoulder washer 72 having a threaded central bore 73 (Fig. 5) registers with the openings in the control bracket 45, friction lever 50, transfer lever 63, and spring washer 70 so as to receive a threaded bolt 74 in order to firmly clamp these parts in position. The shoulder washer 72 preferably carries a metal washer 75 which bears against the transfer lever

63. Interposed between the transfer lever and the bracket 45 may be a friction fiber washer 76. A threaded locking nut 77 is connected to the threaded bolt 74 so as to bear against the shoulder washer 72 in order to releasably maintain these parts in a fixed position. An operating rod 78 has its upper end portion 79 extending through the sleeve 69 and a tubular bearing member 80 (Fig. 6) which is internally threaded as at 81 to receive the external threads on a reduced split portion 82 of the sleeve 69. The upper end of the portion 82 may be provided with flared arms 83 through which extends the outer end of the portion 79 of the rod 78. It will be seen that screw 67 extending into the sleeve 69 bears against the portion 79 of the rod so as to provide means for maintaining the rod 78 in any desired adjusted position.

The foot member 23 is preferably formed with a hinged toe section 84 that is connected to the foot section by a rubber insert 85. The foot member also has an intermediate raised ankle portion 86 and recesses 87 and 88 on opposite sides of the raised portion 86. The lower end or bottom 94 of the calf member 22 is provided with a depending curved lip portion or member 89 (Fig. 1) which bears against a rubber insert 90 in front of and adjacent to the raised portion 86. Within the heel recess 88 is a resilient rubber plug 91 which at its lower end bears against a rubber strip 92 and is of sufficient length as to extend upwardly into a recess 93 formed in the bottom wall 94 of the calf member 22. The rubber inserts 90 and 91 on opposite sides of the pin 95 provide yieldable means for normally maintaining the foot member 23 in substantially a horizontal position, when downward pressure is removed from the toe and heel sections of the foot. A fixed transverse ankle pin 95 is embedded in the bottom 94 of the calf member 22, and the foot member 23 is rotatably connected to the calf member 22 by a looped or inverted U-shaped bolt 96 that extends over the pin 95 and has depending threaded arms 97 projecting through openings 98 in the raised portion 86. The lower ends of the arms 97 extend into a recess 99 so as to be connected to the clamping bolts 100. A friction plate 101 within the recess 99 may be positioned so as to be engaged by the bolts 100 when the U-bolt 96 is secured in position. The U-bolt 96 has extending outwardly therefrom an arm 102 (Fig. 10) which is pivotally connected to a clevis 103 by the pin 104 (Fig. 11). The lower end of the rod 78 extends into an opening 105 in the top of the clevis 103 so as to be secured thereto.

The foot member 23 is movably connected to the lower end of the calf member 22 by the U-shaped bolt 96 through its pivotal connection with the pin 95, so that the foot may be rocked about its pivot in such a manner that the rubber insert 90 will allow a certain forward displacement of the foot member while the rubber plug 91, which is more resilient than the plug insert 90, will allow a greater rearward displacement of the foot member. A yieldable strip of rubber or the like 106 may be positioned below the rubber insert 85 at the ball of the foot and overlaps both the foot member 23 and the toe section 84. The bottom of the foot from the instep over and above the toe 84 may be covered with a strip of leather or the like 107, and a flexible strap or piece 108 may be positioned in the space between the top of the shoe member 23 and the toe 84 so as to underlie the leather covering 107. The

rubber portion 92 of the heel may similarly be covered with a leather piece 109 that is suitably secured to the rear portion of the foot member 23.

In operation of the artificial limb, assuming that the thigh member 21 and the calf member 22 are in vertical alignment and the latch mechanism is released and about to be moved to its locked position to prevent collapse of the knee joint and the user moves his artificial leg forward to take a step (Fig. 15), the knee of the wearer will be in a straight position and as the weight of the body is placed against the heel 92, the rubber plug 91 is depressed within the recess 88 causing the U-shaped bolt 96 to rock on the pin 95 and the arm 102 to be moved upwardly, thus raising the rod 78, which in turn causes the transfer lever 63 and the friction lever 50 together with the metal and fiber washers, and the pin 74 to be rotated relative to the fixed control bracket 45. As the friction lever 50 is operatively connected by the rod 56 to the pawl 41, this upward movement raises the pawl so that the nose 43 is moved and maintained within the opening or catch 29 in the bottom of the knee portion 34 (Fig. 4). In other words, the pawl 41 is moved from its disengaged position as shown in full lines to its locked position as shown in dotted lines in Figure 15. The transfer pin 65 is also moved upwardly in its slot 53 (Fig. 8) so as to bear against the upper wall thereof in order to cause simultaneous movement of the friction lever 50 and the transfer lever 63 when the rod 78 is raised beyond a predetermined limit. It will be seen that during this forward movement of the artificial leg, that the locking mechanism maintains the thigh member 21 in a straight fixed position relative to the calf member 22 so as to prevent buckling of the artificial limb and that it is impossible to bend the leg or for the members to buckle at the knee as the wearer takes a forward step and walks on his artificial leg. As the wearer approaches a vertical position above the artificial leg (Fig. 16), his weight shifts over the knee center and it is no longer necessary for the leg to have a knee lock to prevent it from buckling. It might be mentioned that the instep rubber 90 functions to stop the ankle movement of the foot member 23 as the wearer's body moves forward so that when he depresses the toe portion 84, the artificial limb assumes the position as shown in dotted lines in Figure 16, with the result that as the pressure is applied to the ball of the foot, the yieldable rubber inserts 85 and 90 are compressed and the foot member 23 moved to an inclined position so as to cause the U-shaped bolt 96 to rock on the pin 95 and move the arm 102 downwardly. This movement of the rod 78 lowers the operating rod 78 thus causing the locking mechanism to move the pawl 41 out of engagement with the recess 43 so that the knee joint may be flexed. As the compressed rubber inserts 85 and 90 return to their normal positions, the pawl 41 is prevented from being moved into locking engagement with the recess 43 by the lost motion connection between the transfer pin 65 in the opening 53 of the friction lever 50 which allows a predetermined upward movement of the rod 78 without disturbing the disengaged position of the pawl 41. In order to reengage the pawl it is, of course, necessary to put the weight on the heel 92 of the foot (Fig. 15) which causes the heel rubber 91 to be depressed. During this upward movement of the rod 78 the lost motion between the transfer pin 65 and the

friction lever 50 is taken up by pin 65 engaging the upper wall of the opening 53 (Fig. 8). When the heel rubber 91 and the foot member 23 return to their normal position (Fig. 16), it will not cause disengagement of the pawl 44, which remains locked until the toe 84 of the foot is again depressed. This is due to the fact that when the pawl 41 is moved to its locked position and the foot member returns to its normal horizontal position, displacement of the pawl is prevented by the compression of the spring 62, which functions to take up the excess amount of movement of the friction lever 50 by the engagement of the lug 54 with the lower end of the spring 62 so as to compress the latter as the lug 54 is moved upwardly and away from the head 57 of the connecting rod 56 (Fig. 8), without disturbing or causing any vertical movement to be imparted to the connecting rod 56 and the pawl 41, so that the pawl will remain locked until the toe of the foot is again displaced. In other words, the spring 62 constitutes a lost motion means which functions to take up the excess amount of movement of the friction lever 51 caused by the considerable displacement of the rubber heel member 91 when the latter is compressed. The adjustment of the shoulder friction washer 72 on the bolt 74 is just tight enough to overcome the pressure of the spring 62 on the connecting rod 56 so that the latter remains set against the pressure of spring 62 until it is moved by the transfer pin. Thus, it will be seen that the locking mechanism allows the knee to remain free to swing when it is unlatched and until the weight of the wearer is applied to the heel of the foot. Consequently, the wearer may conveniently bend the artificial limb at the knee to sit down or get up without causing the parts to be moved into locking engagement, and the knee will remain unlocked until the foot is straightened out and pressure applied to the heel (Fig. 15).

In the modified form of the invention shown in Figures 17 to 21 inclusive, the thigh member 110 is pivotally connected as at 111 to the calf section 112 by a transverse pin 113. The bottom 114 of the thigh section 110 which forms the knee joint is provided with a centrally disposed curved slot 115 that extends above the transverse pin 113. Within the slot 115 is a horizontal bar 116 which terminates at one end in a tubular portion or bearing sleeve 117 (Fig. 19) which preferably is locked to the transverse pin 113 by a set screw 118. Extending downwardly and from the opposite end of the bar 116 so as to be movable as a unit therewith, is a depending arm 119, which is clamped or otherwise secured at its lower end as at 120 to a transverse bracket or strap 121 that is connected to the inner forward wall of the calf member 112 by the bolts 122. The lower intermediate portion of a flexible strap 123 passes under a roller 124 carried by the bar 116 and is suitably connected at its upper ends to the waist belt of the artificial leg.

The bottom or knee joint portion 114 of the thigh member 110 adjacent one of the side walls of the slot 115 such as the side 125, is provided with a recess or locking catch 126 that may be protected by a metal plate 127 having an opening registering with the recess 126. A locking mechanism substantially similar to the knee lock previously described, is connected to the rear inner wall of the calf member 112 and preferably includes a vertical bar or member 128 having lateral projecting side arms 129 which are curved

75 The invention is capable of various modifications

to conform with the curvature of the inner rear wall of the calf member 112 so as to be secured thereto by the bolts 130. The bar 128 above the arms 129 may be formed with spaced lugs 131 to which is pivotally connected as at 132 a locking pawl or latch 133. The bar 128 is positioned centrally and substantially in alignment with the slot 115 and in order that the pawl 133 may be moved into and out of locking engagement with the recess 126 in the side wall 125 of the bottom 114, the latch 133 is bent or offset as at 134 (Fig. 20) and has a forwardly extending free portion 135 provided with an arm 136 that engages the recess 126 when the thigh member 110 is moved into alignment with the calf member 112 and the pawl 133 is raised to its locked position. A control bracket 137 is connected as at 138 to the bar 128 and has associated with it a friction lever 139, a transfer lever 140, a spring washer 141, a metal washer 142, and fiber washers 142' which are clamped together by a threaded bolt 143 and nut 142'' so as to be rotatable upon the actuation of the operating rod 144. The rod 144 is pivotally connected as at 145 to the transfer lever 140. The coil spring 146 carried by the connecting rod 147 provides a lost motion connection when the pawl 133 is in locked engagement with the recess 126 and allows the foot member to be returned to its normal position after the heel has been moved to lock the pawl, without disturbing the pawl. The friction lever 139 has an enlarged opening 139' for receiving a transfer pin 140' on the lever 140 for providing a lost motion connection similar in operation to the pin 65 (Fig. 8). The lower end of the operating rod 144 is connected to an inverted U-shaped bolt carried by the foot member and similar in construction and operation to the foot 23 and its associated parts previously described. It will be noted that in this form of the invention the knee lock is not connected to the pin 113, and pawl 133 is offset so as to be moved into and out of locking engagement with its complementary offset recess 126, as contrasted to the centrally disposed latch 41 and its associated parts previously described. Otherwise the construction and operation of both forms of locking mechanisms are the same. In both forms of the invention in order to release the locking mechanism, it is necessary to put the weight on the ball of the foot. To move the latch into locking engagement with its recess when the knee is in a straight position, it is required to put the weight of the user on the heel of the foot.

It will be seen that by reason of the novel locking mechanism as shown in the several figures of the drawing, that simple, efficient, economical and positive means are provided for preventing blockling of the knee joint when the artificial limb is moved forward when taking a step, and that the knee lock can only be released upon the application of pressure to the ball of the foot. Moreover, this locking mechanism allows the knee to remain free to swing when it is unlatched until the thigh member and calf member are moved in alignment and weight is applied to the heel of the foot. The knee lock is compact and constitutes a unitary structure which may be included as a permanent part of an artificial limb or may be readily installed on a used artificial limb at a minimum expenditure of time and effort. Additionally, the parts of the locking mechanism are conveniently positioned so as to be accessible for the purpose of inspection and repair.

tions and improvements as come within the scope of the following claims.

I claim:

1. An artificial limb having in combination, a thigh member provided with a catch, a calf member pivotally connected to said thigh member, a foot member pivotally connected to said calf member, a knee lock mechanism connected to the calf member and including a pawl arranged to be moved into and out of engagement with said catch, a control bracket connected to the calf member, rotatable means connected to said control bracket, means operatively connecting said rotatable means to said pawl, an operating rod connected at its lower end to said foot member, means pivotally connecting the upper end of said rod to said rotatable means, a lost motion connection between the movable means and the pawl for allowing vertical displacement of the operating rod a predetermined distance when the pawl is disengaged from the catch without disturbing the position of the pawl, and yieldable means between the movable means and the pawl for allowing vertical movement of the operating rod without disturbing the pawl when the latter is in locking engagement with the catch, the parts being constructed and arranged so that upon rocking movement of the foot member in one direction to cause the operating rod and the rotatable means to move the pawl into engagement with the catch and upon movement of the foot member in an opposite direction to actuate the operating rod and the rotatable means to disengage the pawl from the catch.

2. An artificial limb having in combination, a thigh member provided with a catch at the lower end thereof, a calf member pivotally connected to said thigh member, a foot member pivotally connected to said calf member, knee lock mechanism connected to the calf member and including a pawl arranged to be moved into and out of engagement with said catch, a control bracket connected to the calf member, a friction lever on one side of said control bracket, means operatively connecting the friction lever to said pawl, a transfer lever on the opposite side of said bracket, means rotatably connecting said levers to said control bracket, an operating rod connected at its lower end to said foot member, and means pivotally connecting the upper end of the operating rod to said transfer lever, the parts being constructed and arranged so that upon rocking of the foot member in one direction for rotating the friction lever and the transfer lever to move the pawl into engagement with said catch when the thigh member is in alignment with the calf member, and when the foot member is rocked in an opposite direction for rotating the friction lever and the transfer lever for releasing engagement of the pawl with said catch.

3. An artificial limb having in combination, a thigh member provided with a catch at the lower end thereof, a calf member pivotally connected to said thigh member, a foot member pivotally connected to said calf member, knee lock mechanism connected to the calf member and including a pawl arranged to be moved into and out of engagement with said catch, a control bracket connected to the calf member, a friction lever on one side of said control bracket, means operatively connecting the friction lever to said pawl, a transfer lever on the opposite side of said bracket, means rotatably connecting said levers to said control bracket, an operating rod connected at its lower end to said foot member,

means pivotally connecting the upper end of the operating rod to said transfer lever, and means providing a lost motion connection between said transfer lever and said friction lever, the parts being constructed and arranged so that upon rocking of the foot member in one direction for rotating the friction lever and the transfer lever to move the pawl into engagement with said catch when the thigh member is in alignment with the calf member, and when the foot member is rocked in an opposite direction for rotating the friction lever and the transfer lever for releasing engagement of the pawl with said catch.

4. An artificial limb having in combination, a thigh member provided with a catch at the lower end thereof, a calf member pivotally connected to said thigh member, a foot member pivotally connected to said calf member, knee lock mechanism connected to the calf member and including a pawl arranged to be moved into and out of engagement with said catch, a control bracket connected to the calf member, a friction lever on one side of said control bracket, means operatively connecting the friction lever to said pawl, a transfer lever on the opposite side of said bracket, means rotatably connecting said levers to said control bracket, an operating rod connected at its lower end to said foot member, means pivotally connecting the upper end of the operating rod to said transfer lever, and yieldable means for providing a lost motion connection between the friction lever and said pawl for allowing vertical movement of the operating rod without disturbing the pawl when the latter is in locked engagement with the catch, the parts being constructed and arranged so that upon rocking of the foot member in one direction for rotating the friction lever and the transfer lever to move the pawl into engagement with said catch when the thigh member is in alignment with the calf member, and when the foot member is rocked in an opposite direction for rotating the friction lever and the transfer lever for releasing engagement of the pawl with said catch.

5. An artificial limb having in combination, a thigh member provided with a catch at the lower end thereof, a calf member pivotally connected to said thigh member, a foot member pivotally connected to said calf member, knee lock mechanism connected to the calf member and including a pawl arranged to be moved into and out of engagement with said catch, a control bracket connected to the calf member, a friction lever on one side of said control bracket, means operatively connecting the friction lever to said pawl, yieldable means providing a lost motion connection between the friction lever and the pawl for allowing displacement of the friction lever without disturbing the position of the pawl, a transfer lever on the opposite side of said bracket, means rotatably connecting said levers to said control bracket, an operating rod connected at its lower end to said foot member, means pivotally connecting the upper end of the operating rod to said transfer lever, and means providing a lost motion connection between said transfer lever and said friction lever, the parts being constructed and arranged so that upon rocking of the foot member in one direction for rotating the friction lever and the transfer lever so as to move the pawl into engagement with said catch when the thigh member is in alignment with the calf member, and when the foot member is rocked in an opposite direction for rotating the friction lever and the transfer lever

11

for releasing engagement of the pawl with said catch.

6. In an artificial limb, a thigh member having a locking catch in the bottom thereof, a calf member, pivot means extending transversely of the thigh member for connecting the upper end of the calf member thereto to provide a movable knee joint, a bar rotatably connected to said pivot means and extending downwardly into said calf member, means connecting said bar to said calf member, a foot member pivotally connected to the lower end of said calf member, a locking pawl pivotally connected to said bar and arranged to be moved into and out of locking engagement with said catch, a control bracket connected to said bar, an operating rod operatively connected at its lower end to said foot member, a friction lever operatively connected to said pawl, a transfer lever pivotally connected to said operating rod, means rotatably connecting said friction lever and said transfer lever to said control bracket, and means providing a lost motion connection between said transfer lever and said friction lever, the parts being constructed and arranged so that upon rocking of the foot member relative to the calf member in one direction, when the thigh member and calf member are in alignment, for moving the pawl into locking engagement with said catch and when said foot member is moved in an opposite direction relative to the calf member for releasing the engagement of the pawl with said catch.

7. In an artificial limb, a thigh member having a locking catch in the bottom thereof, a calf member, pivot means extending transversely of the thigh member for connecting the upper end of the calf member thereto to provide a movable knee joint, a bar rotatably connected to said pivot means and extending downwardly into said calf member, means connecting said bar to said calf member, a foot member pivotally connected to the lower end of said calf member, a locking pawl pivotally connected to said bar and arranged to be moved into and out of locking engagement with said catch, a control bracket connected to said bar, an operating rod operatively connected at its lower end to said foot member, a friction lever operatively connected to said pawl, a transfer lever pivotally connected to said operating rod, means rotatably connecting said friction lever and said transfer lever to said control bracket, yieldable means between the friction lever and said pawl for allowing vertical displacement of the operating rod without disturbing the pawl when the latter is in locked engagement with the catch, and means providing a lost motion connection between said transfer lever and said friction lever, the parts being constructed and arranged so that upon rocking of the foot member relative to the calf member in one direction, when the thigh member and calf member are in alignment, for moving the pawl into locking engagement with said catch and when said foot member is moved in an opposite direction relative to the calf member for releasing the engagement of the pawl with said catch.

8. In an artificial limb, a thigh member having a locking catch in the bottom thereof, a calf member, pivot means extending transversely of the thigh member for connecting the upper end of the calf member thereto to provide a movable knee joint, a bar rotatably connected to said pivot means and extending downwardly into said calf member, means connecting said bar to said

12

calf member, a foot member pivotally connected to the lower end of said calf member, a locking pawl pivotally connected to said bar and arranged to be moved into and out of locking engagement with said catch, a control bracket connected to said bar and having an inwardly extending arm provided with an opening, a friction lever on one side of said control bracket, a transfer lever on the opposite side of said bracket, a spring washer adjacent said friction lever, a friction washer adjacent said transfer lever, said levers and said washers having aligned transverse openings, a clamping bolt extending through said openings for rotatably connecting said levers and said washers to said control bracket, an operating rod pivotally connected at its upper end to said transfer lever, means operatively connecting said friction lever to said pawl, means providing a lost motion connection between said transverse lever and said friction lever, means providing a lost motion connection between said friction lever and said pawl, and means operatively connecting the lower end of said rod to said foot member, the parts being constructed and arranged so that upon rocking of the foot member relative to the calf member in one direction when the thigh member and calf member are in alignment for moving the pawl into locking engagement with said catch, and when said foot member is moved in an opposite direction relative to the calf member for releasing the engagement of the pawl with said catch.

9. A knee lock for artificial limbs including a fixed bracket connected to a limb member, a support rotatably connected to said bracket, a friction lever carried by said support, a transfer lever carried by the support, a pawl pivotally connected to the lock, means operatively connecting the friction lever to said pawl, and an operating member connected to said transfer lever for operating the pawl upon rotation of said levers by the operating member.

10. A knee lock for artificial limbs including a fixed bracket connected to a limb member, a support rotatably connected to said bracket, a friction lever carried by said support, a transfer lever carried by the support, a pawl pivotally connected to the lock, means operatively connecting the friction lever to said pawl, an operating member connected to said transfer lever for operating the pawl upon rotation of said levers by the operating member, and means providing a lost motion connection between the transfer lever and the friction lever.

11. A knee lock for artificial limbs including a fixed bracket connected to a limb member, a support rotatably connected to said bracket, a friction lever carried by said support, a transfer lever carried by the support, a pawl pivotally connected to the lock above said bracket, means operatively connecting the friction lever to said pawl, an operating member connected to said transfer lever for moving the pawl upon rotation of said levers by the operating member, and means for providing a lost motion connection between the friction lever and said pawl.

12. A knee lock for artificial limbs including a fixed bracket connected to a limb member, a pin rotatably connected to said bracket, a friction lever carried by said pin on one side of said bracket, a transfer lever carried by said pin on the opposite side of said bracket, a locking pawl pivoted to said lock above said bracket, a rod connected to said pawl and extending loosely

through said friction lever, a coil spring surrounding said rod and confined between said friction lever and said pawl for providing a lost motion connection between the friction lever and the pawl, and an operating member pivotally connected to the transfer lever for rotating the transfer lever and the friction lever so as to operate said pawl.

13. A knee lock for artificial limbs including a fixed bracket connected to a limb member, a pin rotatably connected to said bracket, a friction lever carried by said pin on one side of said bracket, a transfer lever carried by said pin on the opposite side of said bracket, a locking pawl pivoted to the knee lock above said bracket, a rod connected to said pawl and extending loosely through said friction lever, a coil spring surrounding said rod and confined between said friction lever and said pawl for providing a lost motion connection between the friction lever and the pawl, means providing a lost motion connection between the transfer lever and the friction lever, and an operating member pivotally connected to the transfer lever for rotating the transfer lever and the friction lever so as to operate said pawl.

14. An artificial limb having in combination, a thigh member provided with a catch, a calf member pivotally connected to said thigh member, a foot member pivotally connected to said calf member, a knee lock mechanism connected to the calf member and including a pawl arranged to be moved into and out of engagement with said catch, a control bracket connected to the calf member, a friction member rotatably connected to said bracket, means operatively con-

necting said friction member to said pawl, a transfer member rotatably connected to said bracket, means operatively connecting said transfer member to said friction member, an operating rod connected at its lower end to said foot member, and means connecting the upper end of said rod to said transfer member, the parts being constructed and arranged so that upon rocking movement of the foot member in one direction to cause the operating rod to actuate the transfer member and the friction member to move the pawl into engagement with the catch and upon movement of the foot member in an opposite direction to actuate the operating rod, the transfer member and the friction lever so as to disengage the pawl from the catch.

15. An artificial limb as called for in claim 14 in which the transfer member and the friction member have coacting means for providing a lost motion connection between said members.

JAMES E. HANGER, III.
